CLIP FOR FORM SLEEVES

William P. McCarthy, Kansas City, Mo., assignor to
Ridgewood Instrument Company, Kansas City,
Mo., a corporation of Missouri

Filed Jan. 10, 1968, Ser. No. 10,115

Term of patent 14 years

(Cl. D54—1)

Fig. 1.

Fig. 2.

Fig. 3.

Fig. 4.

Fig. 5.

Fig. 6.

Fig. 7.

FIG. 1 is a rear perspective of the clip for form sleeves, showing my new design;

FIG. 2 is a front perspective view thereof;

FIG. 3 is a top plan view thereof;

FIG. 4 is a bottom plan view thereof;

FIG. 5 is an elevational view of one side thereof;

FIG. 6 is a front elevational view thereof; and

FIG. 7 is a rear elevational view of the sleeve clip.

I claim:

The ornamental design for a clip for form sleeves, as shown.
